UNITED STATES PATENT OFFICE.

LUCIUS PAIGE, OF CAVENDISH, VERMONT.

BRAKE-BLOCK FOR RAILROAD-CARS.

Specification of Letters Patent No. 12,245, dated January 16, 1855.

To all whom it may concern:

Be it known that I, LUCIUS PAIGE, of Cavendish, in the county of Windsor and State of Vermont, have invented certain new and useful Improvements in Railroad-Car Brakes; and I do hereby declare that the following is a full, clear, and exact description of the construction and operation of the same, reference being had to the accompanying drawings, making a part of this specification, in which—

Figure 1, is a plan or top view of a car-truck, with my improved brakes applied to it. Fig. 2, is a detached front view of the screw, and the nut, by which motion is communicated to the device for operating the brakes. Fig. 3, is a plan or top view of the wheel, friction rollers, levers, and springs; the above named parts forming the device 20 by which the brakes are operated. In this view, the upper disk of the wheel is removed. Fig. 4, is a side view of one of the wheels, and one of the sockets with its shoe inserted in it. Fig. 5, is a front view of the 25 wheel, friction rollers, levers, and springs; the same parts as shown in the plan Fig. 3. Fig. 6, is a back view of a socket, with its shoe inserted in it.

Similar letters of reference indicate corresponding parts in each of the figures.

This invention relates to a certain new and useful improvement in rail-road car-brakes; and it consists:—In a peculiar construction and arrangement of the shoes, 35 which bear against the wheels.

To enable others skilled in the art, to make and use my invention, I will proceed to describe its construction and operation.

A, Fig. 1, represents the frame of a car 40 truck, constructed in the ordinary manner; said truck having its wheels, B, attached to it as usual.

Underneath a center crosspiece, C, of the truck, there is a wheel, D, having two friction rollers, (a), (a), placed at opposite points near its periphery; see Figs. 1, 3, and 5. The wheel, D, may be formed of two horizontal disks, (b), (b), connected by small rods, (c), (c), see Fig. 3, on which the 45 friction rollers may be placed as shown in Fig. 3.

The axis, (d) of the wheel, D, passes up through the center crosspiece, C, of the truck, and fits into the center of a lever, E, 50 shown in Figs. 1, and 5; said lever being secured to the axis, (d), by a nut (e). The

lower end of the axis, (d), is stepped in the lower part of a frame, F, underneath the crosspiece, C, more particularly shown in Fig. 5.

G, G, are two levers, the outer ends of which are secured by pivots, (f), in the sides of the frame, F; sufficient play or space being allowed in the frame, F, for the working of the levers. The inner ends of the levers, G, G, bear against the friction rollers, (a), (a), as shown in Figs. 1, 3, and 5.

H, H, are springs, the ends of which bear against the levers, G, G, and press their inner ends against the friction rollers, (a), (a).

I, I, are the brake or cross bars, to which the shoes, J, which will be hereafter described, are attached. These bars, I, are secured or suspended, at each end of the truck frame, by links, K, as will be more 75 fully shown hereafter.

The bars, I, I, are connected to the levers, G, G, by rods, L, L, as shown in Fig. 1. The rods being connected to the levers at the points, (g), (g), as shown in Figs. 1, 3, 80 and 5, and connected to the bars, I, at about their centers, as shown at, (h), (h), in Fig. 1.

To one end of the lever, E, a chain, M, is attached, which passes under a pulley or roller, N at one end of the car frame, and is 85 then attached to a nut, O, through which a hand screw, P, passes; said nut working in a suitable guide frame, Q, as shown in Fig. 2.

At each end of the bars, I, I, there is attached a metallic socket, R, seen in Figs. 1, 90 and 4, and also, 6. The shoes J, are placed in these sockets, and secured therein by means of the face plates, (v), which form one side of the sockets; see Figs. 4, and 6; the face plates being secured to the sockets 95 by means of screw-bolts, (w), which pass through the top and bottom of the sockets and face plates. On the tops of the shoes, J, and also underneath them, are metallic strips, (i), the inner ends of which are intended to be on the same curve as the face of the shoe. These metallic strips are for the purpose of clearing the wheels of snow, and ice which may collect upon them, during inclement seasons, the inner ends of the 100 strips bearing against the treads or faces of the wheels, at the same time, with the shoes.

The shoes may be adjusted, as they are worn, by unscrewing, and thereby loosening the face plates, by which the shoes may be 110 shoved nearer the wheels; the face plates being screwed tightly against the shoes,

when they are properly adjusted, and thereby firmly securing the shoes in the sockets. If necessary, projections, (x), as shown by the dotted lines in Fig. 6, may be made on 5 the inner sides of the face-plates, for the purpose of preventing the least slipping of the shoes in the sockets. Thus, when the old 10 shoes are shortened by use, the making of new ones is obviated; as it will be seen that, by placing the shoes in sockets, they may be used until they are almost wholly worn out; whereas, the ordinary shoes, by being permanently attached to the bars, I, must be replaced by new ones, when shortened a trifle 15 by use.

By operating the hand wheel, on the top 20 of the screw, P, the nut, O, is raised or lowered; and the levers, G, G, are operated; for instance, when the nut, O, is raised, the wheel, D, is turned; and the friction rollers, (a), (a), force out the levers, G, G, which consequently draw the rods, I, I, and shoes, J, toward the wheels, B, causing the shoes to press against the wheels. When the nut, 25 O, is lowered and the chain, M, consequently loosened, the springs, H, H, force back the

levers and wheel and rollers to their original position, and relieve the wheels from the pressure of the shoes. The two positions of the levers, springs, and the wheel, with its 30 rollers, are shown in Fig. 3, by dotted and solid lines.

I do not claim the placing the shoes in sockets or boxes, wherein they remain permanently fixed until worn up so as to be 35 useless; but

What I do claim is—

The improvement of so constructing the shoe, J, and the socket or bearing thereof and applying them essentially as described, 40 that the shoe may extend entirely through and out of the socket in opposite directions and be capable of being moved up to the wheel as fast as occasion may require, until it (the shoe or rubber) is worn up or rendered unfit for further service, my improvement being one of great practical importance and utility. 45

LUCIUS PAIGE.
